US0D1007455S

(12) **United States Design Patent** (10) **Patent No.:** **US D1,007,455 S**
(45) **Date of Patent:** **** Dec. 12, 2023**

(54) **PORTABLE COMPUTER**

(71) Applicant: **Lenovo (Beijing) Co., Ltd.**, Beijing (CN)

(72) Inventors: **Jieyan Zhou**, Beijing (CN); **Yimin Zheng**, Beijing (CN)

(73) Assignee: **Lenovo (Beijing) Co., Ltd.**, Beijing (CN)

(**) Term: **15 Years**

(21) Appl. No.: **35/513,878**

(22) Filed: **Dec. 21, 2021**

(80) **Hague Agreement Data**

Int. Filing Date: **Dec. 21, 2021**

Int. Reg. No.: **DM/219463**

Int. Reg. Date: **Dec. 21, 2021**

Int. Reg. Pub. Date: **Mar. 25, 2022**

(30) **Foreign Application Priority Data**

Jun. 24, 2021 (CN) 202130395143.8

(57) **CLAIM**

The ornamental design for a portable computer, as shown and described.

DESCRIPTION

3.1 is a front view of a portable computer showing our new design;

3.2 is a back view thereof;

3.3 is a left side view thereof;

3.4 is a right side view thereof;

3.5 is a top view thereof;

3.6 is a bottom view thereof;

3.7 is a front, right, bottom side perspective view thereof;

3.8 is a front, left, top side perspective view thereof;

3.9 is a front, left, bottom side perspective view thereof;

3.10 is a back, right, top side perspective view thereof;

3.11 is a back, left, top side perspective view thereof;

3.12 is a front view thereof, showing the portable computer in a folded state;

3.13 is a back view thereof, showing the portable computer in a folded state;

3.14 is a left side view thereof, showing the portable computer in a folded state;

3.15 is a right side view thereof, showing the portable computer in a folded state;

(Continued)

3.16 is a top view thereof, showing the portable computer in a folded state;
 3.17 is a bottom view thereof, showing the portable computer in a folded state;
 3.18 is a front, right, bottom side perspective view thereof, showing the portable computer in a folded state;
 3.19 is a front, right, top side perspective view thereof, showing the portable computer in a folded state;
 3.20 is a front, left, top side perspective view thereof, showing the portable computer in a folded state;
 3.21 is a back, right, bottom side perspective view thereof, showing the portable computer in a folded state; and
 3.22 is a back, left, top side perspective view thereof, showing the portable computer in a folded state.
 The broken lines shown in the reproductions illustrate portions of the portable computer that form no part of the claimed design. The dash-dot-dash broken lines in reproductions 3.1, 3.2, 3.7, 3.8, 3.9, 3.10, 3.11, 3.12, 3.18, 3.19, and 3.20 are included to show a boundary only and form no part of the claimed design.
